BOBBIN SUPPORT FOR WEFT REPLENISHING LOOMS

Application filed April 10, 1930. Serial No. 443,190.

This invention relates to improvements in bobbin supports for weft replenishing looms and it is the general object of the invention to provide a support which will act to position a bobbin quickly in proper location for transfer.

In multicolor weft replenishing looms the bobbins are discharged from one or another of several stacks to fall on bobbin supports.

10 The called bobbin rolls down the supports to a common transfer position and is then inserted into the depleted shuttle. If the bobbin travels from an outside stack or cell it will occasionally acquire sufficient momentum 15 when rolling down the adjacent supports to roll upwardly on the opposite supports before finally coming to rest. It is an important object of my present invention to provide a bobbin support with a distinct shoulder sufficiently pronounced to engage the bobbin and arrest excess or overriding movement thereof.

It is a further object of my invention to provide a pair of bobbin supports each to 25 have a guiding surface which terminates at an abrupt shoulder, the supports being provided with lower bobbin supporting surfaces beyond the shoulder to hold the bobbin tip in transfer position. By such an arrangement 30 a bobbin when rolling over the shoulder will be given an extra downward motion by gravity which is calculated to throw it against the other shoulder. This action takes place irrespective of the direction in 35 which the bobbin approaches the final transfer position.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a vertical section through the lower part of a multicolor magazine showing my improved bobbin supports in normal bobbin supporting relation,

50 Fig. 2 is a top plan view on an enlarged

scale taken in the direction of arrow 2, Fig. 1, and

Fig. 3 is an enlarged view of the lower end of one of my improved supports, the lower portion thereof being shown in section. 55

Referring to Fig. 1 I have shown a loom frame 10 and a magazine 11 provided with a plurality of vertical runways or bobbin guides 12. Although not shown herein, it is to be understood that reserve bobbins await transfer in these guideways and are delivered one by one by mechanism not shown to move toward transfer position. A transerrer arm 13 is suitably pivoted on the magazine frame and is actuated in well-known manner by 60 devices not herein shown to move down when transfer is to take place.

The magazine employs in its construction tie rods two of which are shown at 14 in Fig. 1. Each of these tie rods is provided with a holder 15 rendered angularly and longitudinally adjustable on the corresponding rod by means of a screw 16. Front and back bobbin butt supports 17 and 18 may be provided to operate in the usual manner and when 70 formed as illustrated herein form no part of my present invention other than to cooperate with my improved supports to position a bobbin.

In carrying my invention into effect I provide as illustrated herein two supports for the tip of the bobbin and as each support and its corresponding holder is the same I will describe but one. Each holder is provided with a cap 30 held in position by a bolt 31 secured to the body of the holder 15. The support comprises a closely wound coil spring 32 held for angular and longitudinal adjustment between the cap and its holder and inclined downwardly and toward transfer position as shown in Fig. 1. The upper part of the support has relatively large coils 33 of the same diameter which form a practically smooth guide surface along which the bobbin may roll.

The lower end of the support is formed by several relatively small coils 34 which form in effect a bobbin positioning and holding body having a substantially cylindrical surface separated from the adjacent large coil by 100

a shoulder 35. This shoulder is formed by the wire of which the support is wound and therefore is sufficiently rounded so as to avoid damaging the bobbin. Because of the fact that the support is made of wire no additional precautions are necessary to provide a round edge for the shoulder.

As suggested in Figs. 2 and 3, the lower end of the support may be covered as by rubber or lacquer or similar material. When this coating is dry it fills the spaces between adjacent coils of the spring and thereby prevents the thread W and the bobbin B from being pinched or improperly held by the bobbin support.

In practice, the supports are placed substantially as shown in Fig. 1, and as a bobbin moves toward transfer position the tip will slide down the large coils and arrive at the shoulder. Assuming that the bobbin is coming from the rear or right hand stack as shown in Fig. 1, the bobbin moves to the left and immediately after passing the shoulder 35 of the rear support will be temporarily unsupported and will therefore move downwardly by gravity, being directed toward the opposite shoulder 35 of the other or front bobbin support. In this way the shoulder on the support opposite that down which the bobbin first rolls is effective to engage the bobbin and bring it to proper transfer position quicker than is possible in existing forms of supports.

From the foregoing it will be seen that I have provided a simple form of bobbin support having a shoulder formed so as not to injure the bobbin but effective to arrest excess motion on the part of the bobbin and assist in positioning the latter in proper transfer position with a minimum loss of time. Furthermore, the first shoulder encountered by a bobbin moving toward transfer position enables the bobbin to alter its course and be directed toward the other shoulder.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom wherein a bobbin moves by gravity to transfer position, a pair of inclined bobbin supports to coact and assist in holding a bobbin in transfer position, a shoulder formed on the upper portion as an integral part of one of said supports to engage a bobbin rolling down the other support and prevent the bobbin from moving by reason of its momentum substantially beyond proper transfer position, said supports being resilient throughout their length.

2. In a weft replenishing loom wherein a bobbin moves by gravity to transfer posi-

tion, a pair of inclined yielding bobbin supports, a shoulder formed on the bobbin engaging portion of each of said supports, each shoulder being positioned to engage a bobbin rolling down the opposite support to prevent the bobbin from moving substantially beyond proper transfer position, said supports yielding at any point throughout their length.

3. In a weft replenishing loom wherein a bobbin moves by gravity to transfer position, a pair of inclined bobbin supports along either of which a bobbin may roll toward transfer position, each support having a substantially smooth upper guiding surface along which a bobbin may roll, and an abrupt shoulder formed on the lower portion of each guiding surface, each support having a bobbin positioning surface extending beyond the shoulder to assist in holding the bobbin in proper transfer position, each shoulder being placed to engage and arrest excess motion of the bobbin rolling down the opposite support, the surfaces forming an integral part of the support.

4. In a weft replenishing loom wherein a bobbin moves by gravity to transfer position, a pair of inclined bobbin supports along either of which a bobbin may roll toward transfer position, each support being substantially cylindrical and resilient throughout its entire length and having the end adapted to hold the bobbin in transfer position of smaller diameter than the remainder of the support but formed integral with the support, and a bobbin engaging shoulder adjacent the end of small diameter to engage a bobbin and arrest excess motion thereof.

5. In a weft replenishing loom wherein a bobbin moves by gravity to transfer position, a pair of inclined bobbin supports along either of which a bobbin may roll toward transfer position, each support being formed of a coil spring having coils of two different diameters, the greater part of the length of the support having coils of relatively large diameter and the bobbin positioning end having coils of smaller diameter, and a shoulder separating the coils of different diameters to engage and arrest excess motion of a bobbin moving to transfer position.

6. In a weft replenishing loom wherein a bobbin moves by gravity to transfer position, a pair of bobbin supports to engage opposite sides of a bobbin when the latter is in transfer position, and a pair of shoulders one for each support and formed as an integral part of each support, the supports being inclined and a bobbin when rolling down one support being temporarily unsupported when leaving the first shoulder to be engaged and thereby being directed toward the other shoulder to have the momentum thereof ar-

rested by said second shoulder, said supports being resilient throughout their length.

7. A bobbin support for a weft replenishing loom comprising a spring coiled on itself throughout the length of the support, said spring having two sections of coils of different diameters, the section of larger diameter presenting a guiding surface along which a bobbin may roll toward transfer position, and

10 a shoulder between the sections to engage and arrest excess motion of a bobbin moving toward transfer position.

8. A bobbin support for a weft replenishing loom comprising two substantially parallel integral surfaces along which a bobbin may roll toward transfer position, and an abrupt shoulder separating said surfaces positioned to engage and arrest excess motion of a bobbin moving toward transfer position.

20 9. A bobbin support for a weft replenishing loom comprising a body formed of inherently resilient material throughout its length, said support being formed of two cylindrical integral portions of different diameters and a shoulder located between the portions of different diameters positioned to engage and arrest excess movement of a bobbin moving toward transfer position.

30 10. A bobbin support formed of inherently resilient material and having a relatively long bobbin guiding surface and having a relatively short bobbin positioning surface formed as an integral part of the long surface, said surfaces being out of line, and means defining

35 a shoulder between said surfaces to engage and arrest excess movement of a bobbin moving toward transfer position.

11. A bobbin support formed of a single piece of coiled wire substantially circular in cross section, said support having coils of two different diameters, the larger diameter presenting a bobbin guiding surface and the smaller diameter presenting a bobbin positioning surface, the coil of the larger diameter adjacent the bobbin positioning surface having the rounded portion of the wire of which said adjacent coil is wound exposed to present a smooth shoulder to engage and absorb the momentum of a bobbin moving toward transfer position.

40 12. A coiled spring bobbin support having integral parts of two different diameters separated by an abrupt shoulder, each part being inherently resilient.

55 In testimony whereof I have hereunto affixed my signature.

CARL PHILIP BERGSTROM.
